UNITED STATES PATENT OFFICE.

MICHAEL MUELLER, OF RACINE, WISCONSIN.

LIFTING JACK.

Application filed June 9, 1921. Serial No. 476,186.

To all whom it may concern:

Be it known that I, MICHAEL MUELLER, a citizen of the United States, and resident of Racine in the county of Racine and State of Wisconsin, have invented certain new and useful Improvements in Lifting Jacks; and I do hereby declare that the following is a full, clear, and exact description thereof.

My invention refers to lifting jacks of the screw type, and it has for its object to provide a simple economical and effective jack wherein the actuating mechanism can be selectively shifted, whereby the power can be applied either directly for raising and lowering the jack screw, or indirectly to thus develop a compound lever action, whereby the power is increased, resulting in the diminution of speed when the jack is used for heavy duty.

With the above object in view, the invention consists of certain peculiarities of construction and combination of parts as are hereinafter set forth with reference to the accompanying drawings and subsequently claimed.

In the drawings, Figure 1 represents a side elevation of a jack embodying the features of my invention with parts broken away and other parts in section to more clearly illustrate the details of construction, the section being indicated by line 1—1 of Figure 2.

The Figure 2, a plan view of same with parts broken away and in section as indicated by line 2—2 of Figure 1, the said view showing the lever actuating mechanism coupled for direct action, and

Figure 3, a similar plan view showing the jack lever actuating mechanism arranged for compound movement.

Referring by characters to the drawings, 1 represents a base having a hollow sleeve 2 formed therein, the upper portion of which is shouldered and recessed for an anti-friction bearing 3.

Nested within the recess and resting upon the anti-friction bearing, is the hub 4 of a ratchet or tooth wheel 4', the teeth in this instance being rectangular in formation, whereby the wheel can be conveniently rotated in either direction.

The hub 4 of the wheel is internally threaded for engagement with a jack screw 5, which jack screw is adapted to have telescopic connection with the bore of the sleeve 2. The upper end of the jack screw is pro-

vided with any type of suitable head 5' for engagement with the body to be lifted.

The hub 4 is also extended above the tooth wheel portion thereof for the reception of the apertured end of an arm 6, which arm is mounted to loosely rotate upon the hub terminal, there being a guard housing fitted over the arm and wheel to protect these parts and to also hold them against longitudinal movement, the guard being secured to the base 1.

As best shown in Figures 1 and 2 of the drawings, the arm is provided with a depending trunnion 7, upon which is mounted a double nosed dog 8, the nose extensions of which are arranged to be selectively thrown into engagement with the teeth of the wheel for applying power. After the dog is shifted for this selective engagement, it is yieldingly locked in its working position by a spring controlled plunger 8', which plunger is carried by the arm and is adapted to ride over a central tooth 8'' that projects from the rear wall of the dog as best shown in Figure 2.

The arm 6 is also provided with an upwardly extended pin 9 for engagement with the slotted end 10' of an actuating lever 10. The actuating lever in this instance has secured thereto a fulcrum stud 11 which projects above and below the faces of said lever, and

As shown in Figure 1, the lever is directly coupled to the actuating arm 6 in which position the lower extension of its fulcrum stud 11 is nested within a slot 12, which is formed at the outer end of the aforesaid arm. The lever is held in its position by a cotter pin 13, which extends transversely of the slot and through apertures formed in the divided end portions of the arm.

Hence it will be seen that when the lever is directly coupled with the actuating arm, the wheel hub is rotated directly through its tooth and dog connection to the arm and it will also be noted that said wheel hub can be rotated in either direction, depending upon which nose of the dog is manually shifted for engagement with the teeth. This direct action of the lever that is imparted to the jack screw will rapidly raise the jack screw or lower it.

When it is desired to utilize the jack screw for heavy duty, the lever 10 is removed from its direct coupling connection to the arm 6 by first withdrawing the cotter

pin 13, whereby the lever can be readily removed, and the slotted end 10' of said lever is then caused to engage a fulcrum stud 11', which stud projects upwardly from the top 5 face of the base 1 directly under the arm 6, and in this instance in actual alignment with the pin 9 thereof.

In effecting the engagement between the slotted end of the lever 10 and the stud 11', 10 the upper extension of the fulcrum stud 11 is caused to enter the slot 12 of the arm 6 and thereafter the cotter pin 13 is again slipped into position.

Hence it will be seen that when the detachable actuating lever is fulcrumed to the stud 11', and coupled to the outer end of the arm 6, said lever will form in connection with the arm, a compounding unit whereby a full stroke of the lever will impart in 20 practice a half stroke to the arm 6 for actuating the toothed wheel hub 4, whereby a slow jack screw movement will result with a proportionate increase of power.

While I have shown and described one exemplification of my invention in all its 25 details, I may vary such details, in practice, within the scope of the claims as they may hereafter be interpreted by the mechanic.

I claim:

30. 1. In a jack having a hollow base, a screw spindle mounted therein and a tooth wheel

mounted upon the base, having a hub in threaded union with the spindle; the combination of an arm revolvably mounted about the wheel hub, a dog 6 carried by the lever engageable with the wheel, a shiftable actuating lever, and a coupling means for selectively securing the lever to the arm or base, whereby said arm is actuated to vary speed or power applied to the wheel hub. 40

2. In a jack having a hollow base, a screw spindle mounted therein and a tooth wheel mounted upon the base, having a hub in threaded union with the spindle; the combination of an arm revolvably mounted about 45 the spindle, a spring scroll actuating dog carried by the arm engageable with the tooth wheel, a detachable lever, a fulcrum stud for detachably connecting the lever to the arm, a locking pin for securing the arm 50 and lever together, and a fulcrum stud extending from the base for selective engagement of the lever, the said lever having means for engaging the end of the arm when fulcrumed to the aforesaid stud, whereby 55 movement with relation to the arm is compounded.

In testimony that I claim the foregoing I have hereunto set my hand at Racine, in the county of Racine and State of Wisconsin.

MICHAEL MUELLER.
